UNITED STATES PATENT OFFICE.

FRANK W. DREWS, OF WILLMAR, MINNESOTA.

MANUALLY-OPERATED ROTARY DEVICE.

1,340,026.

Specification of Letters Patent. Patented May 11, 1920.

Application filed November 28, 1919. Serial No. 341,142.

To all whom it may concern:

Be it known that I, FRANK W. DREWS, a citizen of the United States, residing at Willmar, in the county of Kandiyohi and 5 State of Minnesota, have invented new and useful Improvements in Manually-Operated Rotary Devices, of which the following is a specification.

The object of my present sole invention 10 is the provision of a manually-operable rotary device susceptible of being held and operated in such manner as to avert wobbling of the driven spindle, and this notwithstanding the spindle may be operated 15 at a high rate of speed.

To the attainment of the foregoing, the invention consists in the improvement as hereinafter described and definitely claimed.

In the accompanying drawings, hereby 20 made a part hereof:

Figure 1 is a perspective of a rotary device constructed in accordance with my invention.

Fig. 2 is a cross-section showing the drive 25 gearing of the device.

Fig. 3 is a sectional perspective illustrative of a portion of the main frame of the device.

Fig. 4 is a diametrical section through 30 the device.

Fig. 5 is a perspective illustrative of an embodiment of the invention that constitutes a simplification of the embodiment shown in Figs. 1 to 4.

35 Similar numerals designate corresponding parts in Figs. 1 to 4, to which reference will first be had.

Among other elements the device comprises a main frame. The said frame is 40 made up of a central sleeve 1, a web 2, a circular wall 3 on the web, and braces 4 interposed between the sleeve 1 and the circular wall 3. It will also be observed that the web 2 is provided with a central sleeve 45 bearing 5, and that a shank 6 extends radially from the circular wall 3 so as to carry a convenient radially disposed handle 7. In the web 2 and adjacent to the inner side of the wall 3 is formed a circular 50 groove 8.

Arranged within the circular wall 3 of the main frame is an interiorly toothed annular gear 9, and in the inner side of said gear 9 is formed a groove 10 which, in conjunction with the groove 8, forms a race for

anti-friction balls 11. The said gear 9 is carried by an outwardly projecting spider 12, and at the central portion of said spider is arranged a socket 13 to receive and to transmit rotary motion to a spindle 14 on 60 which is keyed a spur gear 15, said spur gear being intermeshed with the spur gear 16, and the spur gear 16, in turn, being intermeshed with a spur gear 17 that is also intermeshed with the teeth of the annular 65 gear 9. The spur gears 16 and 17 are mounted on sub-shafts 18 that extend from the web 2, as illustrated. At 19 the spindle 14 is provided with a collar, and between said collar and the sleeve 1 is interposed a 70 washer 20. I would also have it understood that I prefer to interpose the anti-friction balls 21 between the washer 20 and the collar 19. Shown as carried upon the spindle 14 is a drill chuck 22. I would have it understood, however, in this connection that the spindle 14 may be used to carry any desired implement or device that it is sought 75 to rotate at a high rate of speed.

Fixed with respect to the annular gear 9 80 is one end of an operating crank 30; the said crank 30 having a loose hand grasp 31 mounted upon it at an intermediate point of its length and having its opposite end alined with the spindle 14 and journaled at 85 32 in a rest 33 that may be and preferably is placed against the shoulder of the operator.

In the practical operation of the device as described, the drill or other implement in 90 the chuck 22 is opposed to the surface to be drilled, and the handle 7 is held in one hand of the operator while the operator bears with his shoulder against the rest 33. Then when the operator turns the gear 9 95 through the medium of the hand-grasp 31 and the crank 30, it will be manifest that the spindle 14 will be powerfully turned at a high rate of speed.

The modified construction shown in Fig. 100 5 is a material simplification of that shown in Figs. 1 to 4. In the modified construction, the annular interiorly toothed gear 9^a is provided with a crank 30^a equipped similarly to that before described. Said 105 gear 9^a is also arranged in a frame and within the circular wall 3^a on which is a radial handle 6^a. The frame also comprises braces 4^a which are interposed between the major portion of the same and a sleeve 1^a 110

in which latter is journaled a spindle 14^a, equipped with a chuck 22^a. At its inner end the spindle 14^a is provided with a gear 17^a that is intermeshed with the gear 9^a.
5 From this it follows that while the embodiment shown in Fig. 5 is a material simplification of that illustrated in Figs. 1 to 4, it is possessed of practically all of the advantages ascribed to the embodiment of Figs.
10 1 to 4.

Having described my invention, what I claim and desire to secure by Letters-Patent, is:

15 A manually operable rotary device comprising a frame having an annular portion

and a sleeve offset from said annular portion and fixed thereto through the medium of interposed braces and also having a handle extending radially outward from said annular portion, a spindle journaled in 20 the said sleeve and connected with a device it is designed to rotate, a gear on said spindle, an annular interiorly toothed gear bearing and revoluble in the annular portion of the frame and connected with the first- 25 named gear, and a crank fixed to said annular interiorly-toothed gear.

In testimony whereof I affix my signature.

FRANK W. DREWS.
